UNITED STATES PATENT OFFICE.

JOHN C. POETZ, OF LEONIA, IDAHO.

MOLDING CORE.

Application filed December 21, 1925. Serial No. 76,584.

My present invention relates to improvements in molding cores especially designed for use with plastic material in the construction of concrete building structures involving cellular or hollow monolithic walls.

The primary object of the invention is the provision of a hollow implement of this character which may be constructed of sheet metal or other suitable material and provided with means for centering and accurately placing the core in position for pouring or tamping the plastic concrete material. The cores are used preferably in rows, in desired numbers in the process of constructing courses or layers in the wall and they are spaced apart in order that the material may fill the spaces formed between adjoining implements or cores. Means are provided for accurately and conveniently spacing the cores with relation one to another and such spacing means contemplate interchangeable parts for use with the cores whereby the desired distances between the cores or the cells formed about them may be predetermined. The cores are removable and are fashioned with features which facilitate their removal or withdrawal from the formed cell after the concrete or plastic material has set.

The invention consists in certain novel combinations and arrangements of parts for accomplishing the above indicated purposes and functions as will hereinafter be more fully set forth and claimed.

In the accompanying drawings I have illustrated one complete example of the physical embodiment of my invention wherein the parts are combined and arranged in accord with the best mode I have thus far devised for the practical application of the principles of my invention.

Figure 1 is a perspective view of a hollow core embodying my invention.

Figure 2 is a vertical sectional view of the core showing it in a section of the concrete wall.

Figure 3 is a transverse sectional view of the core at line 3-3 of Figure 1.

In carrying out my invention the cores may be fashioned in uniform sizes and shapes and employed for molding cells or spaces of complementary size and shape in the concrete wall, and these cells may be spaced at uniform distances apart, the dis-

tance being predetermined to suit different conditions in the structure.

In the present exemplification of my invention I have utilized a generally rectangular shaped hollow core for fashioning a generally rectangular shaped cell C the upper end of which is closed by a metal reinforcing plate P in Figure 2 where a portion of the concrete wall W is shown in section.

The core body 1 may be made up of sheet metal or other suitable material with bulging or convex sides and rounded corners 2 to facilitate withdrawal or removal of the core from the cell after the concrete is set. The core body is open at top and bottom and these parts are closed by removable plates 3 and 4 the former for the bottom and the latter for the top of the open end core.

The bottom plate is secured within the open lower end of the core body and is fashioned with a central perforated boss 5 struck up from the plate for the reception of a tie bolt 6 having an enlarged head 7 on its lower end below the bottom plate.

The bottom plate as here used is a flat generally rectangular plate with rounded edges to conform to the interior of the core body and fit snugly and neatly within the interior of the open lower end of the core body. At its four sides the bottom plate is fashioned with turned-down lugs 8 that are seated in the concrete base when the core is placed in position, and with turned up lugs 9 which are slipped or inserted in the loops or complementary straps 10 one of which is attached at the inner side of each of the four walls of the core body. These lugs 8 are used in centering the core in place and seating it firmly on the concrete base preparatory to filling the spaces about the cores and tamping the concrete into place.

The top plate 4 of the core is preferably dished as shown to strengthen it and to form an annular groove 12 at its under side to neatly fit over the top edge of the core body, and a retaining shoulder or flange 13 of the dished plate fits over the top edge and down the side of the core body a sufficient distance to form a cover for the interior of the core body and prevent access of filling material to the interior of the core.

The threaded end of the central tie bolt 6 is passed up through a bolt hole 14 in the

center of the top plate, and a clamp nut 15 is threaded on the end of the bolt against the top face of the top plate. By turning home the nut on the projecting bolt-end the two heads or plates 3 and 4 of the core are clamped between the bolt head 7 in the boss 5 and the nut 15 on the top of the top plate 4 of the core.

In use the cores are placed in rows or in other formations and spaced uniform distances apart from their centers and these distances may be varied by the use of gage devices preferably carried on the top plates of the cores. For this purpose the top plate is fashioned with gage-lugs 16 at three of its sides for contact with adjoining gage lugs as indicated in Figure 2, and a larger or longer gage lug 17 is provided on the fourth side of the top plate for contact with a lateral form 18 used in erecting the concrete wall. It will be apparent that by lengthening the gage lugs 16 and placing in contact complementary lugs on adjoining core plates the distances between centers of the cores will be increased and the resulting cells C will be spaced farther apart. Regardless of the shape of the top plate and cross sectional shape of the core body, these gage lugs may be diametrically disposed with relation to the core body for coaction with complementary gage plates.

From the above description taken in connection with my drawings the utility of the implement and its mode of use will be apparent, and it will be evident that the implement as thus constructed and used is com-

pact, well braced, comparatively light in weight, durable, and efficient in the performance of its required functions.

Having thus fully described my invention, what I claim as new and desire to secure by Letters Patent is—

1. The combination with a core body having an open top and bottom, of removable top and bottom plates, a tie bolt and nut connecting said plates, and means for retaining in position the clamped top and bottom plates.

2. The combination with a core body having an open top and bottom, of removable top and bottom plates and a connecting clamp bolt, guide devices on the exterior of the bottom plate for properly seating the core, and gage devices on the exterior of the top plate for positioning the core relative to an adjoining device.

3. The combination with a core body having a removable top plate and a clamping bolt, said plate having a closure shoulder for engagement with the core body, and gage devices on said plate for co-action, with complementary devices on an adjoining laterally disposed core.

4. The combination with a core body having interior retaining loops, of a removable plate having lugs to co-act with said loops, a top plate for the core and a clamping bolt for said plates.

In testimony whereof I affix my signature,

JOHN C. POETZ.
